United States Patent Office

Des. 230,922

Patented Mar. 26, 1974

230,922

SEAT

Marilyn Lewis, Beverly Hills, Calif., assignor to Hamburger Hamlets, Inc., Beverly Hills, Calif.

Original design application Dec. 15, 1969, Ser. No.
20,495, now Patent No. 222,537. Divided and this application Mar. 1, 1971, Ser. No. 119,992

Term of patent 14 years

Int. Cl. D6—02

U.S. Cl. D6—59

Fig. 1

Fig. 2

FIG. 1 is a perspective view of a seat constructed according to principles of this invention; and

FIG. 2 is a back view of the seat of FIG. 1.

20,495, filed Dec. 15, 1969, now U.S. Pat. No. D. 222,537.

I claim:

The ornamental design for a seat, as shown.
